APPARATUS FOR UTILIZING SOLAR RADIATIONS FOR THERAPEUTIC PURPOSES

Application filed November 27, 1928. Serial No. 151,168.

This invention relates to an apparatus for utilizing solar radiations for therapeutic purposes.

As is well known, certain of the solar radiations, e. g. the ultra-violet rays, are highly bactericidal and it is these radiations which I utilize in my invention.

Various devices have been put on the market for artificially producing ultra-violet rays for therapeutic treatments but these devices do not, and cannot produce ultra-violet rays of the same bactericidal quality as those found in the solar radiations, and my invention contemplates the utilization of the ultra-violet ray of the solar radiations.

The general object of this invention therefore is to provide a method and apparatus whereby the sun's rays may be used for therapeutic purposes.

20 A specific object of the invention is to provide means for utilizing the various colored rays or heat waves of the sun for the treatment of various diseases.

Another object of the invention is to provide means for using the colored rays and the heat waves simultaneously to treat the same area.

Another object of the invention is to provide means for utilizing any one of the color rays of the ultra-violet radiations independent of the other color rays.

Still another object of the invention is to provide means for treating both sides of an object with the sun's rays while the rays are projected from one side only.

Other objects and advantages of this invention will be apparent from the following description taken in connection with the accompanying drawings wherein:

Fig. 1 is a front face view of the apparatus used for projecting the sun's rays.

Fig. 2 is a section taken on line 2—2 of Fig. 1 showing the construction of the lens holder.

45 Fig. 3 is a section taken on line 3—3 of Fig. 2 showing the construction of the prism holder.

Fig. 4 is an elevation showing the cone attachment applied to the lens holder.

50 Fig. 5 is a front view of a lens holder which

may at times be used in connection with the main lens.

Fig. 6 is a front face view of a light screen which may be used for screening out the undesired color rays.

Fig. 7 is a diagrammatic view of the sun's rays after passing through a lens.

Fig. 8 is a diagrammatic view of the sun's rays after passing through a lens showing the manner of screening out the undesired color rays.

Fig. 9 is a view similar to Fig. 8 showing means for enlarging the color rays for treating a larger area.

Fig. 10 is a diagrammatic view showing the method of utilizing both heat and color rays for treating the same area.

Fig. 11 is a diagrammatic view showing the method of projecting the rays onto either side of an object.

Fig. 12 is a side elevation of a set up for producing the effect shown in Fig. 8, and

Fig. 13 is an enlarged top plan detail.

Referring again to the drawings I have shown my device for projecting the sun's rays generally at 10 in Fig. 1. This device consists of a base 11 mounted on castors 12 and adapted to support a hollow vertical standard 13. Mounted on the standard 13 for vertical movement there is a frame 14 having horizontally extending arms 15 and 16 integral therewith and arranged intermediate its length. The frame 14 is adapted to be clamped in any desired vertical position by a clamping screw 14'.

The arm 15 is provided with a trunnion 17 on which a yoke 18 is rotatably mounted. This yoke 18 is provided at its ends with bearings 19 and 20 which supports a lens frame 21. The yoke 18 is adapted to be clamped in any desired position by a clamping screw 17' which acts against the trunnion 17. The yoke 18 is provided with an indicating pointer 18' which acts in conjunction with a scored dial 18'' mounted on the projection or arm 15 of the frame 14.

The lens frame 21 comprises a circular body portion 22 having on its outer periphery bosses 23 in which are secured trunnions 24 and 25. The trunnion 24 extends through

the bearing 19 of yoke 18 and has on its outer end a pointer 27 which moves over a scored dial 28 on the bearing 19. The trunnion 25 extends through the bearing 20 and is adapted to be clamped in any position by clamping screw 29 mounted on the bearing 20.

On the sides of the body 22 peripheral flanges 30 and 31 are provided. The flange 31 is of less diameter than the body 22 and forms a shoulder against which I arrange a rubber gasket 32 which engages a lens 34. This lens is retained in place by a ring 35 which has screw threaded engagement with the body 22 and bears against another rubber gasket 36. This construction allows the lens 34 to be readily removed to enable lenses of other sizes and substances to be inserted in the base 22.

The flange 30 is provided with a pair of bayonet joint slots 37 for retaining a shutter device 38 in the flange 30, which is provided with a pair of bayonet joint pins 39. The shutter device 38 may be similar to a camera shutter of large size and may be operated by a lever 38'. The flange 31 is provided with a pair of bayonet joint slots for the reception of a pair of bayonet joint pins 41 of a cone 42 (see Fig. 4).

The arm 16 of the frame 14 has a rod 43 mounted thereon and adapted to be moved vertically about a horizontal pivot 43' and clamped in any desired position by a clamping screw 44. The rod 43 is provided with an indicating pointer 45 which acts in conjunction with a graduated dial 46 secured on the frame 14.

The rod 43 has a circular frame 47 arranged thereon. This frame is adapted to be moved about a vertical pivot 48 and may be clamped in any desired position by a hand screw 48'. The frame 47 is also provided with an indicating pointer 49 which acts in conjunction with a scored dial 50 on the link 43. The frame 47 is provided with bearings 51.

Within the frame 47 I arrange another circular frame 52 provided with trunnions 53 mounted in the bearings 51 of the frame 47. Mounted on the outer end of one of the trunnions 53 is an indicating pointer 54 which acts in conjunction with a graduated dial 55 secured to the frame 47. The trunnions 53 of the frame 52 are rotatable in the bearings 51 and may be clamped in any desired position by a clamping screw 65.

The frame 52 is provided with bearings 57 and 58 (see Fig. 3) for rotatably supporting a prism frame 59. The prism frame 59 is provided with bosses 60 and 61 in which are secured trunnions 62 and 63. The trunnion 62 extends through the bearing 57 and has an indicating pointer 64 mounted on its outer end to act in conjunction with a graduated dial 57' arranged on the bearing 57.

65 The trunnion 63 extends through the bearing

58 and is adapted to be secured in any position by a thumb screw 65. The prism frame 59 is provided with an aperture 66 in which a prism 67 is mounted. The prism 67 is held in place in the frame 59 by thumb screws 68.

The weight of the frame 14 and the various devices supported by it is partially counterbalanced by a weighted member 69 which works inside of the hollow standard 13 and is connected to the frame 14 by a cord 70 running over a pulley 71 mounted at the top of the standard 13.

By the provision of adjustable mounting as previously described and by using the indicating pointers and dials, the instrument may be readily set for treatment by providing charts which indicate the point at which the various devices should be set for treating various ailments.

The cone 42 as shown in Fig. 4 includes a metal end rim 72 which fits around the flange 31 of the lens base 21 and has secured to it the pin 41 which engages the bayonet joint slot 40 of flange 31. Secured to the rim 72 there is an outwardly extending hollow conical portion 73 preferably made of non-inflammable opaque material and provided with a hollow conical removable metal tip 74 at its outer end. The cone 42 is so constructed that when it is used with the proper lens such as 34 (see Fig. 2) the focal point of the lens will be within the conical tip 74.

For treating various ailments it may at times be desirable to use one or more auxiliary lenses in conjunction with the main lens shown in Fig. 1, and for this purpose I have indicated in Fig. 5 an auxiliary lens stand generally at 75 for supporting an auxiliary lens 76 mounted in a yoke 77 which is supported in a standard 78. The lens 76 is adapted for movement in relation to the yoke 77 and the yoke is adapted to be vertically moved in relation to the standard 78 and both the lens and the yoke are shown as adapted to be secured in any desired position by clamping screws.

For screening out the undesirable rays I have shown in Fig. 6 a color screen 80 which may be opaque and non-inflammable. This screen is mounted on a rod 80 which is supported on one portion of a universal joint 82 to allow a wide range of movement for the screen 80. The joint 82 is mounted on a rod 83 pivotally secured to an upright 84 and adapted to be secured in any desired position relative to the upright by a clamping screw 85. The upright 84 is slidably supported in a standard 86 and may be secured in any desired vertical position by a clamping screw 87 on the standard 86.

As is generally known in the art, the solar radiations are not simply white light, but are composed of the seven primary colors. When the solar radiations are caused to pass through a lens, as in Fig.

7, the different colors of the spectrum are brought to focus at different points and a color spectrum is formed along the line connecting these points, the violet coming to a focus at the point nearest the lens, if convex, and the red at a point farthest therefrom. After passing the line of focus, the colors spread out. The color spectrum as a whole is composed of 80% invisible infrared, or heat rays, 13% visible rays, or white light, and 7% invisible ultra-violet.

The ultra-violet rays are of different wave lengths or variety, and it is these ultra-violet rays which I use for therapeutic purpose.

15 The different colored rays are used for treating different ailments, and to obtain the best results a specific color ray is concentrated on the part to be treated, and to do this it is therefore necessary to screen out 20 the other colored rays which are not wanted.

25 In Fig. 8 I show diagrammatically the method of treating with the blue violet rays. The solar radiations 100 are projected through a lens 34 to the point (beyond the focal point 102) where the blue violet rays predominate at the outer circumference of the projected rays. At this point the screen 30 80 is arranged to intercept the undesirable rays and let only the blue violet rays pass. With the form of screen shown in Fig. 6 part of the blue violet rays will unavoidably be obstructed, but a special screen of more intricate design may be used which will allow all of the blue violet rays to pass while 35 all the undesirable rays will be screened out, but for the purpose of illustration the screen shown in Fig. 6 will suffice.

40 After the undesirable color rays have been screened out the blue violet rays are passed through another lens 104 and are projected onto the portion being treated, which is indicated at 105, the blue violet rays being shown at 106.

45 In Fig. 9 I show the same method of projecting and screening the color rays as in Fig. 8, and in addition I provide a lens 108 for spreading the blue violet rays to cause the same to treat a larger area as indicated at 109 on the surface 110 being treated.

50 In Fig. 10 I show a method of selecting the color rays by means of a prism 111 and projecting the same on the area 112 of the part 113 which is to be treated. In addition to treatment with the color rays, the area 112

55 is being treated by heat rays 114 which are projected through a first lens 115 and a second lens 116. The lens 116 is constructed to reduce the burning effect which is produced by the lens 115. By treating a patient with both 60 the color and heat rays the bactericidal qualities of the color rays act to kill the injurious bacteria while the heat rays act to cause a better circulation of the blood.

65 In Fig. 11 I show a method of treating an object on both sides by employing but a single

beam of rays. In this method I project the solar radiations 117 through a lens 118 and screen out the undesirable color rays at the right distance past the focal point 119 by a screen 120. The undesirable color rays 121 are then projected through a diffusing lens 122 into a beam 123. A portion of this beam 70 impinges against one side of the object 124 to be treated, the remaining rays 125 are allowed to pass beyond the object 124 to a reflector 126 from whence a beam 127 is cast upon the 75 side of the object 124 opposite to the rays 123.

In Fig. 12 I have shown a side elevation of my apparatus set up to accomplish the treatment described in connection with Fig. 8. The solar radiations 128 are projected through the lens 34 to form a beam 129. The undesirable color rays are screened out at the proper distance beyond the focal point 130 by the screen 80, and the desirable color rays 131 are allowed to pass and are projected through the lens 76, whence a beam 132 is projected upon a patient being treated.

The cone as shown in Fig. 4 is used for momentary burning of an object such as a wart, carbuncle, mole, etc. The solar radiations are projected through the lens 34 into the cone 73 and the focal point of the projected rays come within the metal tip 74.

75 The shutter 38 is closed and the tip 74 is placed over the object to be treated and then the shutter 38 is opened for a predetermined period, and closed again and in this way the concentrated heat rays are allowed to burn the object for a time which may be as short 80 as desired.

95 In this application I have shown only a few of the methods of using my invention, but it will be understood that various forms of apparatus may be used and that the color and heat rays may be projected through as many lenses or prisms as desired to obtain the best results without departing from the spirit of 100 my invention.

105 What I claim is:

1. In a therapeutic apparatus means for 110 directing solar rays upon an area comprising a base, a standard on said base, an arm on said standard, a lens frame mounted on said arm, a lens in said frame, a hollow member on said lens frame and projecting therefrom, said member having an opening therein, and a removable closure for said opening.

115 2. In a therapeutic apparatus means for 120 directing solar rays upon an area comprising means for producing ultra-violet rays from solar radiations and for selecting a specific color ray from said ultra-violet rays, said means comprising a lens through which the solar radiations are projected and a screen located at a point beyond the focal point of 125 said lens to screen out the undesirable color rays and allow the desired color rays to pass.

3. In a therapeutic apparatus means for 130 directing solar rays upon an area comprising

- a base, a standard on said base, a frame mounted to move vertically on said standard, an arm on said frame, a lens frame universally mounted on said arm, a lens in said frame, 5 a shutter mounted on said lens frame, means to hold said shutter in position, a hollow member adjacent to said lens frame, said member having an opening therein, said opening substantially coinciding with the focal plane of 10 said lens.
4. In therapeutic apparatus, means for directing solar rays upon an area comprising a support, means on said support for obtaining the ultra-violet rays from solar radiations, means for selecting a specific color ray from said ultra-violet rays, means for concentrating said ray upon an area, means for projecting the solar heat waves upon the same area as said color rays, said color selecting 15 means including a prism, said prism being mounted for universal movement for obtaining said desired color ray from said solar radiations, said means for projecting heat waves upon said area including a lens through 20 which the solar radiations pass to form a beam.
5. In therapeutic apparatus, means for directing solar rays upon an area comprising means for projecting ultra-violet rays from 25 the solar radiations, and for selecting a specific color ray from said ultra-violet rays, said means comprising a lens through which the solar radiations are projected and a screen located at a point beyond the focal point of 30 said lens to screen out the undesirable color rays and allow the desired color rays to pass, and means to concentrate said desired rays, said concentrating means comprising a second lens through which said selected rays are 35 projected.
6. In a therapeutic apparatus, means for directing solar rays upon an area comprising a base, a standard on said base, a pair of oppositely directed arms on said frame, a yoke 40 rotatably mounted on one of said arms, means to hold said yoke in set position, said yoke having bearings therein, a lens frame rotatably mounted in said bearings, means on said 45 bearings for holding said lens frame in set position, the other arm having a rod mounted thereon for movement about a horizontal axis, means for holding said arm in set position, an indicating scale and pointer for indicating the angular position of said rod, a 50 frame mounted on said rod to turn about a vertical pivot, means to hold said frame in set position, an inner frame rotatably mounted on said first frame, a prism frame rotatably mounted on said inner frame and a prism 55 in said frame.
7. In a therapeutic apparatus, means for directing solar rays upon an area comprising a base, a standard on said base, a frame mounted to move vertically on said standard, 60 a pulley on said standard, a counter weight 65
- movable in said standard, a flexible cable connecting said counter weight and said frame, an arm on said frame, a yoke rotatably mounted on said arm, a scale fixed on said one arm, a pointer mounted on said yoke, means to hold said yoke in set position, said yoke having bearings therein, a lens frame rotatably mounted in said bearings, a scale on said yoke, a pointer mounted to rotate with said lens frame, means on said bearing for holding said lens frame in set position, said lens frame having a pair of peripheral flanges thereon, and means on said frame for removably holding a lens thereon, a shutter mounted in one of said peripheral flange, means to hold said shutter in position, said other flange having a hollow conical member thereon, said member having an opening at its outer end, and a removable closure for said opening.
- In testimony whereof, I hereunto affix my signature.
